UNITED STATES PATENT OFFICE.

DANIEL CAHILL, OF PIQUA, OHIO.

UNION SUIT.

1,129,331.

Specification of Letters Patent. Patented Feb. 23, 1915.

Application filed June 21, 1913. Serial No. 774,980.

To all whom it may concern:

Be it known that I, DANIEL CAHILL, a citizen of the United States, residing at Piqua, in the county of Miami and State of Ohio, have invented certain new and useful Improvements in Union Suits; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in nether garments of the knit fabric closed crotch type.

The object of the invention is to provide a garment of this type which has a flexible 20 closed crotch which allows the legs of the garment to be made of the same size, to the end that the wearer may comfortably dress on either side.

Referring to the accompanying drawings, 25 Figure 1 is a front elevation of a knitted closed crotch garment as constructed according to my invention; and Fig. 2 is a plan view of the crotch and flap portions of the garment.

30 Referring more particularly to the drawings, 1 and 2 represent overlapping flap portions of the garment which cross in the manner shown in Fig. 2 and the upper edges 3 of which are united to the rear portion of the body 4 of the garment along a seam 5. The flaps 1 and 2 are provided with leg extensions 6 forming gussets. The edges 7 of these flaps and gussets are united to the body portion of the garment along seams 8. The 35 edges 9 of said gussets are united to the front of the leg portions 15 along seams 10, while the edges 11 of both of the flaps 1 and 2 are united to the lower end of the facing

12 along the seam 13. Adjacent to the edges 11 and seam 13 of the garment, the flaps 1 45 and 2 are united to form the closed crotch. This is accomplished by means of a broad opened end seam consisting of two rows of 50 stitches 14 which lie parallel with the wales of the fabric and unite the flaps at their central portions. Owing to the absence of cross stitching at the end of this seam, the legs 15 at the crotch may be of the same size and 55 will have a uniform elasticity in stretching, thereby permitting the wearer to dress comfortably on either side, and the crotch to remain closed under all conditions of wear.

I claim:

A new article of manufacture, comprising 60 a union suit having two overlapping flap pieces which form the central back portion thereof, and together with the body portion form the seat portion of the garment, the outer longitudinal edges of said flap pieces and the upper transverse edges being united 65 respectively to the leg and body portions of the garment throughout said longitudinal and transverse edges, the lower inner longitudinal edges of said flap pieces and the lateral edges extending therefrom being 70 united with the leg portions at the inner leg seams, said lateral edges being overlapped and united by two parallel perpendicular lines of stitches and forming the crotch of the garment, and the upper inner longitudinal edges of said flap pieces being disconnected in the crotch where said parallel lines 75 of stitches terminate to the upper transverse seam which unites said flap pieces to the back body portion of the garment. 80

In testimony whereof I affix my signature, in presence of two witnesses.

DANIEL CAHILL.

Witnesses:

R. J. McCARTY,
MATTHEW SIEBLER.
